(57) **CLAIM**

The ornamental design for a vibration control and noise insulation material, as shown and described.

DESCRIPTION

FIG. 1 is a top plan view of a first embodiment of a vibration control and noise insulation material.

FIG. 2 is a bottom plan view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged perspective view of the claimed design and the neighboring area.

FIG. 8 is an enlarged view of the encircled portion in FIG. 1.

FIG. 9 is a sectional view taken along Line 9-9 in FIG. 8.

FIG. 10 is a top plan view of a second embodiment of a vibration control and noise insulation material.

FIG. 11 is a bottom plan view thereof.

FIG. 12 is a front elevation view thereof.

FIG. 13 is a rear elevation view thereof.

FIG. 14 is a left side elevation view thereof.

FIG. 15 is a right side elevation view thereof.

FIG. 16 is an enlarged perspective view of the claimed design and the neighboring area.

FIG. 17 is an enlarged view of the encircled portion in FIG. 10; and,

FIG. 18 is a sectional view taken along Line 18-18 in FIG. 17.

The broken lines shown in the drawings illustrate portions of the vibration control and noise insulation material that form no part of the claimed design.

The dash-dot broken lines indicate the boundary and form no part of the claimed design.
